UNITED STATES PATENT OFFICE.

AUGUST P. HILDEBRANDT, OF PHILADELPHIA, PENNSYLVANIA.

MUSIC-LEAF TURNER.

No. 897,534.

Specification of Letters Patent.

Patented Sept. 1, 1908.

Application filed December 30, 1907. Serial No. 408,465.

To all whom it may concern:

Be it known that I, AUGUST P. HILDEBRANDT, a citizen of the United States, residing at Philadelphia, in the county of Philadelphia and State of Pennsylvania, have invented certain new and useful Improvements in Music-Leaf Turners, of which the following is a specification.

This invention relates to music leaf turners, the object being to provide a music leaf turner which is so constructed that it can be readily attached to a music stand or piano, and the arms connected to the leaves of the music book or sheet of music, so that by simply pressing the bulb with the foot, the leaves can be turned in succession, whereby the musician will not have to stop to turn the leaves.

Another object of my invention is, to provide adjustably mounted operating arms, so that they can be readily adjusted to suit any size book or sheet of music.

Another object of my invention is, to provide very novel means for holding these arms in a locking position, so that when they are released, they will be carried over to the other side, carrying with them the sheets of music.

Another object of my invention is, to provide very novel means for operating the tripping arms, which will automatically move step by step, so as to engage the locking levers in succession.

Another object of my invention is, to provide very novel means for adjusting, the means for giving the step like motion to the operating arm, whereby the arm can be readily moved back into its original position.

These objects are obtained by the novel arrangement and construction of parts hereinafter fully described and shown in the accompanying drawings in which:

Figure 1, is a perspective view of my improved music leaf turner, showing the application of the same to a music stand, supporting a book, the arms being connected to the leaves desired to be turned. Fig. 2, is a transverse section through the casing of the music leaf turner, the operating mechanism being shown in elevation. Fig. 3, is a longitudinal section through the casing of my improved music leaf turner, the operating mechanism being in elevation, and, Fig. 4, is a perspective view of tripping arm, and means for moving said arms step by step.

In the drawings A, indicates an ordinary music stand provided with the usual book rack on which is secured a book, which is held thereon by an elastic band B, one end of which is connected to the book rack, and the other to an eye formed in the upper end of the casing C, of my improved music leaf turner, which is provided with a plurality of slots in its top, through which arms D, extend, which are carried by disks E, loosely mounted on a longitudinal shaft F, secured in the ends of the casing, each disk being provided with an eye E', through which a spring G, extends, which is secured at its inner end in a bore formed in the shaft, and is provided at its outer end with an eye G², which fits around the arm D, whereby the arms will be thrown over in a reverse position from what is shown in Fig. 2 when released, as will be hereinafter fully described, the disks being held in their proper position on the shaft in respect to the slots by collars secured on the shaft and the springs.

Slidably mounted on the arms D, are sleeves H, provided with set screws for locking them in their adjusted position, and having rods I, extending upwardly therefrom on which are adjustably mounted sleeves J, provided with fingers K, carrying clasps K', for attaching the fingers to the leaves of the book, the sleeves J, being secured in their adjusted position by thumb screws, and it will be seen by this arrangement, the rods and fingers can be adjusted to suit any size book, or sheet of music.

The disks E, are provided with cam lips E², adapted to be engaged by the angle end L', of angle locking levers L, which are loosely mounted on a longitudinal shaft L², secured in the casing, the angle ends of the lever being held into engagement with the shoulder of the cam lips by the counter-balance weight of the horizontal member L³, of the lever L, and it will be seen that as these levers are thrown out of engagement with the cam lips, the spring will rotate the disk and carry with it the arms for turning the leaf or page. For operating these levers one at a time, as it is desired to turn the leaves of the book, I provide a tripping mechanism as shown at M, which comprises a tripping arm N, having an angle end, which is carried by a collar N', provided with a notch into which fits the longitudinal rib of a shaft O, which is mounted in the bearings secured to the ends

of the casing, whereby the collar can slide on the shaft, but is prevented from being rotated thereon.

Secured on the shaft O, is a sleeve P, which is provided with a downwardly projecting finger P', which is connected to a downwardly projecting finger O', carried by the shaft O, adjacent its other end, the fingers being connected together by a thin strip of aluminium O², for the purpose hereinafter fully described.

Secured to the sleeve P, is one end of a coil spring Q, which surrounds the shaft O, and has its other end connected to the collar N', of the tripping finger N, whereby the tendency of the tripping arm is to move towards the sleeve P.

Extending upwardly from the collar N', is an arm R, which extends between a pair of parallel shafts S—S', mounted in bearings, secured to the ends of the casing, the shafts being provided with inwardly projecting fingers S²—S³, the fingers of the shaft S', being longer than the fingers S², of the shaft S, and these fingers are so arranged in respect to the locking levers L, that when the arm R, is in engagement with the first one of the fingers S³, the tripping arm will be directly under the first locking lever, whereby when said tripping arm is forced upwardly, the angle end of the locking lever will be thrown out of engagement with the cam lip, so as to release the disk which will carry over with it the first arm of the series of arms D. As the arm R, is oscillated by the movement of the tripping arm upwardly, it will be thrown out of the path of the first finger of the series of fingers S³, which will release the collar, so as to allow the spring to draw it into engagement with the first finger of the series of fingers S², and as the arm swings back into position, it will be thrown out of engagement with the finger S², into engagement with the second finger of the series of fingers S³, which will bring the tripping arm under the next one of the locking levers, it of course being understood, that this operation is continued until all of the locking levers have been tripped.

Secured on the shafts S—S', are a pair of gears T—T', meshing with each other, the gear T, being provided with a crank arm T², to which is connected an operating rod T³, which extends out through a slot formed in the casing, and by means of which the fingers can be thrown up into a vertical position, out of the path of the arm R.

Extending outwardly horizontally from the collar N', is an operating rod N², which extends through a longitudinal slot in the side of the casing, and it will be seen that when the fingers are thrown up into a vertical position, by pushing or drawing the rod forward, the tripping arm can be brought back into position, and locked by turning the fingers down again, it of course being

understood, that the arms D, had been thrown over into a set position and locked by the locking levers.

For swinging the tripping arm N, I secure in the casing opposite the strip of aluminium O², a casing U, provided with a plunger U', adapted to engage the strip of aluminium O², and for operating the plunger, I connect a flexible tube V, which extends down along the standard of the music stand in eyes, and is provided with a rubber bulb V', at its end, whereby when said bulb is pressed with the foot, the plunger U', will be forced into engagement with the strip O², whereby the shaft O, will be oscillated, so as to swing the tripping arm up into engagement with the locking lever.

From the foregoing description it will be seen that I have provided a very novel music leaf turner, which is exceedingly simple and cheap in construction, and one which is provided with very novel means for moving the tripping arm step by step into engagement with the locking levers.

Having thus described my invention what I claim as new and desire to secure by Letters Patent is:—

1. A music leaf turner comprising a plurality of spring actuated arms, means for locking said arms, a movable tripping arm adapted to engage said locking means, and means for imparting a step by step motion to said tripping arm.

2. A music leaf turner comprising a plurality of spring actuated loosely mounted disks carrying arms, locking levers for engaging said disks, a tripping arm for engaging said locking lever, and means for imparting a step by step motion to said tripping arm.

3. The combination with a casing provided with a plurality of slots, of a shaft secured longitudinally in said casing, a plurality of spring actuated disks loosely mounted on said shaft provided with cam lips, arms carried by said disks extending out through said slots, locking levers for engaging said cam lips, a tripping arm for engaging said levers in succession, and means for operating said tripping arm.

4. The combination with a casing, provided with a plurality of slots, of a longitudinal shaft mounted in said casing, a plurality of disks loosely mounted on said shaft carrying arms extending out through said slots, springs for operating said disks, levers for locking said disks, a slidably mounted tripping arm for engaging said levers, and means for throwing said tripping arm into engagement with said levers, together with means for sliding said tripping arm, for the purpose described.

5. In a music leaf turner, the combination with a casing provided with a plurality of slots, and having a longitudinal shaft ar-

- ranged therein, of a plurality of disks provided with cam lips loosely mounted on said shaft, arms carried by said disks extending out through said slots, rods adjustably mounted on said arms, fingers adjustably mounted on said rods carrying clasps, locking levers for engaging said cam lips, and means for disengaging said locking levers from said cam lips in succession.
- 10 6. In a music leaf turner, the combination with a plurality of spring actuated disks carrying arms, of locking levers engaging said disks, a tripping arm for engaging said locking levers, means for throwing said arm into engagement with said levers, together with means for imparting a step by step movement to said tripping arm, whereby said tripping arm will engage the locking levers in succession.
- 15 7. In a music leaf turner, the combination with a casing provided with a plurality of slots, of a longitudinal shaft mounted in said casing, a plurality of disks loosely mounted on said shafts, springs for operating said disks, arms carried by said disks extending out through said slots, provided with means for attaching it to the leaves of the book, locking levers for engaging said disks, a shaft mounted in said casing carrying a tripping arm, extending
- 20 under said levers, means for rocking said shaft, together with means for moving said tripping arm step by step on said shaft.
- 25 8. In a music leaf turner, the combination with a shaft, of a plurality of disks mounted
- on said shafts, carrying arms extending out through said slots, and provided with cam lips, locking levers engaging said cam lips, a slidably mounted collar carrying a tripping arm for engaging said locking levers, an arm carried by said collar, shafts arranged on each side of said arm, provided with inwardly projecting fingers, and means for rocking said tripping arm, whereby said fingers will be engaged in succession.
- 30 9. In a music leaf turner, the combination with a casing provided with a plurality of slots, and having a longitudinal shaft secured therein, of a plurality of spring actuated disks provided with cam lips loosely mounted on said shaft, arms secured to said disks extending out through said slots carrying rods having fingers adjustably mounted thereon, provided with clamping means, pivoted locking levers, adapted to engage said cam lips, a tripping arm for disengaging said locking levers from said cam lips on the disk, pneumatic means for operating said tripping arm, together with means for moving said tripping arm into engagement with said locking levers in succession.
- 35 10 In testimony whereof I have signed my name to this specification in the presence of two subscribing witnesses.

AUGUST P. HILDEBRANDT.
